UNITED STATES PATENT OFFICE.

NORMAN W. NUTT, OF TRENTON, NEW JERSEY.

ELECTRIC SWITCH.

1,366,701.

Specification of Letters Patent. Patented Jan. 25, 1921.

Application filed June 14, 1919. Serial No. 304,147.

To all whom it may concern:

Be it known that I, NORMAN W. NUTT, a citizen of the United States, residing in Trenton, in the county of Mercer and State 5 of New Jersey, have invented an Improvement in Electric Switches, of which the following is a specification.

The invention relates to quick action snap switches of the same general type as disclosed in my copending application filed of even date herewith, Serial No. 304,146, and presents several variant but equivalent forms of connection between the key spindle and the switch plate, as will be more particularly pointed out in the annexed specification, in connection with the accompanying drawings, in which;

Figure 1 is a longitudinal section of a lamp socket involving the invention, the outer shell or casing being omitted.

Fig. 2 is a vertical section on line 2—2 of Fig. 1;

Fig. 3 is a rear elevation of the switch plate and the cam for operating the same.

Fig. 4 is a longitudinal section through the switch plate.

Fig. 5 is a rear elevation of the locking plate.

Fig. 6 is a sectional edge view thereof.

Figs. 7 and 8 are side elevations of the switch spindle and switch plate with alternative means connecting the two together.

Referring to the drawings, 1 and 2 indicate the upper and lower halves of a lamp socket supporting base of porcelain or the like, the respective halves being chambered to provide a housing for the contacts and switch mechanism, and the contacting faces of the two members being provided with longitudinal alining grooves which constitute bearings for the switch spindle when the two halves are secured together by screws or fastening means, in the usual manner. The right hand bearing for the spindle

projects within the recess formed within the base to provide an extended support for the spindle. The upper section of the base carries the usual contact 20 connected with wire terminal 21, and the lower section is provided with a spring 22 having the usual center contact 23 disposed within the screw-threaded socket member 24.

The spindle 3 is provided with a squared section 3' at its outer end and with the usual thumb piece 19 on the opposite end. Mounted on the cylindrical portion of the

spindle is a washer 18, which, when the spindle is in position, abuts against the outer end of the sleeve-like bearing formed in the base on one side, and against two lugs 60 17, extending radial of the shaft and preferably formed by pinching the metal of the shaft on opposite sides, said washer thereby holding the shaft against axial movement in the base. Loosely mounted on the forward 65 end of the spindle 3, so as to be capable of longitudinal movement and rotative movement thereon, is a switch plate 4, preferably stamped from sheet metal, having a central annular portion with two oppositely disposed lateral arms having upturned ends 5 constituting contacts for coöperation with the spring contacts 20 and 22, and two shorter arms at right angles to the contact arms and terminating in upturned ears 6, 6. 75 The central portion of the switch plate is provided with an enlarged circular opening through which the squared end of the spindle 3 projects and which admits of the switch plate being moved either axially or 80 circumferentially with respect to the spindle. The long arms of the switch plate are provided with detents 7, 7, which are preferably formed as bosses pressed outward from the rear of the plate, as illustrated in Figs. 85 3 and 4. Between each of the detents 7 and the center of the switch plate is formed a similar boss 7^a which constitutes a cam member by means of which the switch plate is moved axially of the spindle, as will be here- 90 inafter explained.

In Fig. 1, the switch plate is operatively connected with the spindle by means of a helical spring 15 which extends through a transverse hole in the spindle and has 95 its free ends looped through suitable holes in the upturned ears or lugs 6, 6 on the short arms of the switch plate, as shown in Figs. 1 and 2, so that when the spindle is turned and the switch plate is retained in locked 100 position, the spring is placed under tension and tends to rotate the switch plate in the same direction as the spindle.

Mounted in a squared recess formed in the two halves of the base and concentric with the spindle 3 is a stop plate 9 having squared sides and a dished central portion having an enlarged circular opening 10. Each of the sides of the stop plate is provided with a recess 11, the edges of which constitute 105 stops with which the bosses 7, 7 on the switch plate engage to retain said switch 110

plate locked in either opened or closed relation.

5   Mounted on the squared end 3' of the spindle 3 and occupying the dished portion of a stop plate 9 is a cam or dog 12 having oppositely extending radial cam members and a central lug or flange 14 provided with a squared central opening 13 by means of which the cam or dog is locked to the spindle 10 for rotating movement therewith, but is slideable thereon when the parts are to be assembled or adjusted. The radial fingers of the cam or dog 12 coöperate with the rounded cam-like bosses 7^a on the switch plate and 15 serve to force the switch plate axially along the spindle until the detent bosses 7 on the switch plate are disengaged from the stop members 11 on the stop plate 9. The boss or flange 14 on the cam member 12 constitutes a journal for the squared end of the shaft. This boss 14 fits snugly within the 20 opening 10 in the stop plate 9.

As illustrated in Fig. 1, the switch is 25 shown in open position with the contact members 5 of the switch plate out of engagement with the contact springs 20 and 22. Upon turning the spindle 3 for a portion of a revolution, the cam member 12 partaking of the movement of the spindle rides 30 under the rounded bosses 7^a on the switch plate and forces the latter along the shaft toward the handle of the spindle until the detents 7 on the switch plate are disengaged from the stops 11, 11 on the stop plate 9, 35 which latter is rigidly held in the base. The rotation of the spindle while the switch plate is stationary imposes a tensional stress on the helical spring 15, and as soon as the switch plate is unlocked from the stop plate 9 this 40 stress is sufficient to impart a rapid rotary movement to the switch plate, which rotary movement continues until the detents 7, 7 thereon are opposite the other set of stops 11, 11 on the stop plate and drop into the recesses 45 forming the stops and lock the switch plate to the stop plate. As the stops 11 on the plate 9 are spaced at intervals of 90°, it will be apparent that each successive rotary movement of the switch plate is 90°, and to 50 effect this movement the spindle may be turned in either direction. Due to the increased tension of the spring 15 connecting the spindle with the switch plate, the rotary movement of the latter is very rapid so

that when the spindle is turned to open the 55 switch, contact members 5, 5 of the switch plate are disengaged so quickly from the spring contacts 20 and 22, that sparking between the contacts is practically eliminated.

In the modification shown in Fig. 7, the 60 single helical spring shown in Fig. 1 is replaced by two short helical springs 15' and 16', which are connected respectively to perforated gears 20 struck from the metal of the shaft and perforated lugs 6, 6 on the short arms of the switch plate. The operation of this form of the invention is substantially identical with that of the form shown in Fig. 1, but the double spring arrangement 65 renders the snap action of the switch a little 70 smoother and more positive, inasmuch as the short helical springs 15' and 16' will be individually placed under somewhat greater tension by the partial rotation of the spindle than would be the long unitary spring 75 shown in Fig. 1.

In Fig. 8, the upturned lugs 6 on the switch plate 4 are provided with lateral flanges 6', 6', and the spindle is provided with two transverse perforations through 80 which are passed two spring rods or wires 15'', the outer ends of which lie between the flanges 6' on the switch plate. In this form of the device, when the spindle 3 is partly rotated, the spring rods 15'' are bent 85 between the points of engagement with the spindle and the switch plate and impose a strain on the switch plate which tends to rotate the latter, so that when the switch plate is moved out of engagement with the stop 90 plate, this stress becomes effective to rotate the switch plate through 90° and until it is again locked to the switch plate in the manner hereinbefore described.

What I claim is:—

95   A snap switch comprising an axially movable rotary switch plate and a stationary plate having coöoperative engagement therewith, a rotary spindle, a coil spring connection between the spindle and switch plate, 100 said spring passing through an opening in the spindle, and substantially parallel to said switch plate for rotating said switch plate.

NORMAN W. NUTT.
